UNITED STATES PATENT OFFICE.

CHARLES EISLER, OF BLOOMFIELD, NEW JERSEY, ASSIGNOR TO WESTINGHOUSE LAMP COMPANY, A CORPORATION OF PENNSYLVANIA.

MACHINE FOR MAKING FILAMENT-SUPPORTS FOR INCANDESCENT LAMPS.

1,338,499.

Specification of Letters Patent. Patented Apr. 27, 1920.

Application filed November 12, 1915. Serial No. 61,690.

To all whom it may concern:

Be it known that I, CHARLES EISLER, a citizen of the United States, and a resident of Bloomfield, in the county of Essex and State 5 of New Jersey, have invented a new and useful Improvement in Machines for Making Filament-Supports for Incandescent Lamps, of which the following is a specification.

My invention relates to machines for 10 forming filament-supporting arbors for incandescent electric lamps, and it has for its object to provide a machine of the character indicated which shall be simple in construction and substantially automatic in operation, and which shall be capable of producing large numbers of finished articles with a minimum amount of labor and attention.

More specifically, the object of my invention 20 is to provide a machine for automatically and continuously forming incandescent lamp arbors of the type having two or more enlargements or "buttons", and to equip such machines with certain new and 25 improved operating mechanisms, as will hereinafter more fully appear.

In the accompanying drawings, Figure 1 is a side elevational view of a machine constructed in accordance with my invention; 30 Fig. 2 is a plan view of the machine illustrated in Fig. 1; Fig. 3 is a transverse view, partly in elevation and partly in section, of a portion of the mechanism shown in Fig. 2; Fig. 4 is a side view, partly in elevation and partly in section, illustrating the plunger mechanism which forms a part of my machine, Fig. 5 is a diagrammatic plan view illustrating the manner in which the lamp arbors are formed by the machine, and 40 Figs. 6 and 7 are elevational views showing details of the apparatus shown in Fig. 5.

The present machine consists essentially of an intermittently rotated drum mounted upon a horizontal axis and provided with 45 axial peripheral slots which are adapted to receive short lengths of glass rod. The rods, in the several slots, are carried, in a step-by-step movement, into contact with gas flames, in order to heat the rods locally, and they are 50 then brought into engagement with reciprocating plungers which apply longitudinal pressure to the rods and thus form thickened portions or buttons thereon. Means are also provided for feeding the short rods 55 to the machine, for removing the finished ar-

bors therefrom, and for rotating the arbors while they are being heated and pressed.

Referring now to Figs. 1, 2 and 3 of the drawing, standards 1 and 2, connected by cross beams 3 and 4, form a frame which 60 supports bearings 5 for a horizontal main shaft 6, on one end of which is loosely mounted a sprocket wheel 7 for transmitting power to the shaft 6 from any convenient source, (not shown). The sprocket wheel 7. 65 carries a fixed clutch member 8 coöperating with a movable clutch member 9 which is slidably keyed to the shaft 6 and is biased to its disconnected position by means of a compression spring 10. A clutch-shifting lever 70 11 is provided for forcing the clutch member 9 into engagement with the clutch member 8 to cause the shaft 6 to rotate with the sprocket wheel 7.

Between the bearings 5, the shaft 6 carries a cam 12, two sprocket wheels 13 and 14 and a cam plate 15, all these parts being rigidly secured to the shaft 6. Loosely supported upon ball bearings 16 between the sprocket wheel 14 and the cam plate 15, is a 80 drum composed of a series of disks or wheels 17, 18 and 19, the disk 17 and 18 being bolted to a flanged sleeve 20, and the disk 19 being bolted to a second sleeve 21 which is concentric with the sleeve 20 and slidably attached thereto by means of keys 22. This arrangement permits of the adjustment of the drum for handling glass rods of many different lengths. Each of the disks 17, 18 and 19 is provided with peripheral flanges 90 23 and 24 which are transversely slotted at intervals, giving the disks the appearance of fine-toothed gear wheels. The slots in the several disks should be disposed opposite to one another and each set of adjacent slots 95 forms a receptacle for receiving a glass rod and for carrying it through the several operations to which it is subjected.

For imparting a step-by-step rotative movement to the drum formed by the disks 17, 18 and 19, a ring 25, provided with both external and internal ratchet teeth, is attached to one side of the disk 17 by means of screws 26, and the external ratchet teeth are engaged by a pawl 27 carried by a lever 28 which is pivotally mounted upon a pin 29 that is adjustably secured in a vertical slot 29^a in the frame of the machine. The end of the lever 28 opposite to the pawl 27 carries a roller 30, which is pressed into 110

engagement with the cam 12 by means of a spring 31 surrounding the stud 29 and engaging the lever 28. The cam 12 is provided with four teeth or projections which 5 successively engage the roller 30 and oscillate the lever 28 above its pivot. It will be evident that, when the main driving shaft 6 is rotated in a clockwise direction, as seen in Fig. 1, the disks 17, 18 and 19 will be rotated in unison in a counter-clockwise direction. The vertical adjustment of the pivot pin 29 in the slot 29^a permits the use of pawl levers having arms of different relative lengths, whereby the distance advanced 10 by the toothed drum at each stroke of the pawl may readily be varied. The internal ratchet teeth formed on the ring 25 are engaged by a holding pawl 27^a which is pivoted to the standard 2 and is oscillated by 15 means of a lever 28^a carrying a roller 30^a which engages the cam 12. The holding pawl 27^a accentuates the position of the drum at each interruption of its movement and prevents the drum from advancing while the 20 button-forming operations are being performed.

A bracket 35 is carried by the standard 1 at the right of Fig. 1 and supports a standard 36 upon which is mounted a feeding hopper 37 for receiving glass rods 38 cut to the required length. As the toothed drum is moved in a counter-clockwise direction, one of the glass rods is received in each of the transverse slots and, if two rods should be 30 taken up in a single slot, the extra rod would be held back by means of a set of adjustable fingers 39 which are carried by a horizontal rod 40 supported on the standard 36. An inclined chute 41 is mounted adjacent to the toothed drum at the left of Fig. 1, being carried by supports 42 and 43 that are adjustably mounted on a bracket 44 attached to the frame of the machine. The chute 41 receives the finished arbors from 40 the drum and delivers them to a receptacle (not shown). During their passage from the feeding hopper 37 to the chute 41, the glass rods are constantly rotated in the slots of the drum by means of a series of endless steel bands 45, one of which is provided for each of the disks that compose the toothed drum. The bands 45 correspond in width to the space between the peripheral flanges 23 and 24 of each disk and are driven by means of 50 two sets of positively rotated driving rollers 46 and 47 disposed at opposite ends of the machine, as shown in Fig. 1. The driving rollers 46 are mounted upon a shaft 48 carried by a bearing bracket 49 secured to the 55 frame of the machine. The shaft 48 also carries a sprocket wheel 50 which is driven by means of a chain 51 from the sprocket wheel 14 that is attached, as stated above, to the shaft 6. The driving rollers 47 are 60 mounted upon a shaft 52 carried in a bearing

53 formed in the bracket 35. The shaft 52 also carries a sprocket wheel 54 which is driven by means of a chain 55 from the sprocket wheel 13 secured to the shaft 6. It will be observed that both sets of rollers 70 46 and 47 are positively driven in unison, by means of the sprocket wheels and chains just described, an arrangement which insures that every part of the belts shall be driven at uniform speed without slackening 75 or binding. Both of the sets of rollers 46 and 47 are driven in a clockwise direction, as seen in Fig. 1, and the bands 45, after leaving the rollers 47, pass between tension rollers 56 and 57, around guide rollers 58 80 and around the upper portion of the toothed drum to the rollers 46, where the direction of the bands is reversed and they again pass over the top of the toothed drum and return to the rollers 47. If one of the bands 85 45 should break, it could readily be replaced without dismantling the machine, and this is a feature of advantage over prior machines of this general character.

It will be observed that each glass rod, as 90 it is carried around the top of the drum, is inclosed between the upper and lower runs of the bands 45, the tension of the bands being so adjusted that the rods are caused to rotate in their several slots. The tension of 95 the bands 45 is maintained and adjusted by means of three sets of rollers 60, 61 and 62, the rollers 60 being carried in suitable forks attached to rods 63 which are slidably mounted in a support 64 carried by a vertical post 65 attached to the bracket 49. The rollers 61 and 62 are similarly mounted upon rods 66 and 67 which are slidably mounted in supports 68 and 69 carried by cross arms 70 that are themselves supported by a post 71 attached to a bracket 72 bolted to the standard 1 of the machine frame. All of the rollers 60, 61 and 62 may be provided with springs 73 for increasing the pressure with which they bear upon the 100 bands 45, and the rollers 61 or 62 may be omitted, if desired.

For maintaining the rods in proper positions in the slots in the toothed drum, the feeding hopper is provided with a side extension 80 which serves as a gage for corresponding ends of the rods, while a similar gage 81 is adjustably carried by a rod 82 supported upon a post 83 carried by the bracket 72. Immediately adjacent to the 110 guide extension 80 of the hopper 37, and in alignment therewith, is an anvil plate 84 carried by a rod 85 that is supported in a bracket 86 secured to the machine frame. An arm 87 of the bracket 86 carries a rod 115 88 which is attached to the guide extension 80 and serves as a support therefor.

Disposed opposite to the anvil 84 and beyond the end of the guide 81 are two reciprocating hammers or plungers 94 and 95, the 120

- construction of which will be hereinafter more fully described. These plungers, when reciprocated toward the anvil 84, press against the ends of the glass rods which are, 5 at that moment, presented to them and which have been locally heated to soften the glass sufficiently to enable it to expand under the longitudinal pressure and to thereby form enlargements or buttons in the rods.
- 10 For the purpose of locally heating the rods, two gas burners 90 and 91 are provided, these gas burners being stationarily mounted adjacent to the rotating toothed disks which carry the rods, as shown in Fig. 2, and being 15 supplied with gas through suitable tubes 92 and 93, respectively. The burners 90 and 91 are preferably mounted upon adjustable supports 89 in order that their relative positions may be varied as desired. The rods, 20 in their progress upon the toothed drum, first encounter the flame of the burner 90, which softens a portion of each rod near one end. A button is then formed by the pressure of one of the plungers. By means of a 25 burner 91, the rod is then heated at its end opposite to the button already formed, and the heated end is finally flattened by means of a second plunger, the first button having meanwhile cooled and become solid.
- 30 The hammers or plungers 94 and 95 which accomplish the foregoing results are similar in construction and are best shown in Fig. 4. The two plungers are mounted upon arms 96 and 97 of the bracket 72, each of 35 these arms being provided with a bearing 98 within which is slidably mounted a tubular member 99 which is secured for reciprocation in the bearing 98 by means of a key 100. The rear end of the tubular member 40 99 is reduced in internal diameter to receive the screw threaded end of a plunger member 101 which carries, at its opposite end, a hardened steel tip 102. The forward portion of the member 101 is enlarged to substantially the internal diameter of the tubular member 99 and is slidably secured in the member 99 by means of a key 103. A compression spring 104 is confined between the enlarged portion of the member 101 and the 45 inner end of the member 99 for the purpose of maintaining the plunger member 101 in the position shown, which position may be varied by means of a micrometer screw 105 and a lock nut 106.
- 50 The tubular member 99, near its forward end, is provided with pins or screws 108 which extend horizontally from opposite sides of the collar 107 and are engaged by the bifurcated arms of a fork 109 that is 55 carried by the upper end of a lever 110. The lever 110 is pivotally mounted upon a bracket 111 and is biased to the position shown by means of a spring 112. The lever 110, at its lower end, carries a roller 113 60 which co-operates with cam projections 114 that are secured to the sides of a cam plate 15 which, as stated above, is secured to the shaft 6 for rotation therewith. It will be evident that the plunger will be reciprocated intermittently by means of the cam projections 114 and that, if the plunger encounters a resistance greater than the force with which the spring 104 presses the plunger forwardly, the plunger will be permitted to yield to such resistance, the member 101, in 70 such case, being permitted to slide within the movable member 99. It will be observed that the length to which the member 101 extends from the tubular member 99 may be readily and accurately varied by means of 75 the micrometer screw 105, thus permitting the machine to operate upon many different lengths of glass rods. The micrometer adjustment may be made without interrupting the operation of the machine. 80
- When it is desired to form very large buttons upon the glass rods, the plungers or hammers are provided with means for applying preliminary pressures to the ends of the rods. Such auxiliary pressing devices are illustrated in Figs. 5, 6 and 7. The plunger member 101, associated with the hammer 94 carries, at its forward end, a laterally extending bracket member 130 which is removably clamped to the plunger 85 101 by means of a screw 131 and is provided with a screw-threaded aperture 132 adapted to receive an adjusting screw 140. One end of the screw 140 is provided with a knurled head 141, and the other end of the screw 140 90 engages the flexible free end of the gage member 81. It will be observed that at each forward movement of the plunger 94, the end of the screw 140 will press the gage member 81 into contact with several of the 95 rods which have been locally heated by the gas flame 90 and that such pressure will operate to form a preliminary enlargement in each of the rods so engaged. The effect of this preliminary pressure is that, when 100 the plunger itself finally presses against the end of each rod, the final button which it forms will be larger than when no preliminary pressure is applied. 105
- For a purpose similar to that just described, the plunger 95 is provided with a laterally extending bracket 133 which is clamped to the plunger member 101 by means of a screw 134 and is provided with an aperture 135 to receive a short rod 136. 110 The rod 136 is adjustably secured with relation to the bracket 133 by means of a set screw 137 and carries a plate 138, the working face of which is formed in a series of progressively offset flat surfaces. By this 115 arrangement, the softened end of each rod is given four slight impacts as it advances toward the final button-forming position and each of these impacts operates to 120 slightly enlarge the end of the rod. 125 130

In order to control the movement of the toothed drum, and particularly to prevent the drum from moving backwardly in the intervals between the successive impulses applied by the pawl 27, a brake is provided, which, in the form shown, consists of one or more bands or chains 115, which are secured at one end to the cross beam 4 of the machine frame, extend beneath the drum and in contact therewith, and are secured, at their opposite ends, to a rod 117. The rod 117 extends through an opening in a cross beam of the machine frame and is screw-threaded to receive a wing-nut 119 which varies the compression of a spring 120 surrounding the rod 117. By the arrangement shown, the tension of the bands 115 may be readily varied in accordance with the requirements of the machine.

As the toothed drum and the endless bands 45 move adjacent to the gas filaments 90 and 91, they become heated to a considerable degree, and cooling means are therefore provided for both the drum and traveling bands. As shown, the rollers 47 are partly inclosed within a semi-cylindrical casing 121, which may be supplied with water or other cooling liquid, but which I prefer to connect to a source of compressed air, the supply of which is regulated by means of a valve 122. A blast of air is also supplied to the lower side of the toothed drum, conveniently through a pipe 123 extending axially beneath the drum and supplied with air through a tube 124 controlled by a valve 125.

The general operation of the machine may be best explained by reference to Fig. 5, which shows, diagrammatically, the progress through the machine of a series of glass rods. Each rod 38 is first received from the hopper 37 in one of the sets of corresponding slots in the disks 17, 18 and 19 and is intermittently carried by the drum in its step-by-step movement, the distance traversed by each slot, and, consequently, by each rod, at each movement of the machine being equal to the distance between two adjacent slots. As it advances, the rod is first heated locally by means of the burner 90, being constantly rotated by means of the bands 45, and, when the rod is opposite to the plunger or hammer 94, the plunger presses the hammer against the rod and thus forms the first enlargement or button. The rod continues to rotate, thus insuring that the button shall be substantially circular, and is carried to the burner 91, the interval between the two burners being sufficient to enable the first button to cool and harden before the second button is formed. The end of the rod is softened sufficiently to be flattened by the hammer 95, and, still rotating, it proceeds to the chute 41, through which it falls into a suitable receptacle.

It is to be noted that the hammers 94 and 95 reciprocate in unison and perform their working stroke while the toothed drum is at rest. The gas flames are preferably so adjusted with respect to the plunger that each button, after being formed, is caused to rotate for a short time in the flame. This insures that the button shall be circular, and also serves to anneal the glass, which is crystallized somewhat in the button-forming operation.

The machine which I have shown and described is capable of making many thousands of lamp arbors per day and requires the attention of only one operator who cuts the rods into the required length, places them in the feeding hopper and removes the finished arbors delivered by the machine. By reason of the numerous adjustments that may be made in the machine, many different sizes of arbors may be manufactured thereon. By suitably varying the longitudinal positions of the hammers or plungers, the buttons formed on the arbors may be of any desired size, from a slight enlargement of the rod to a large flat button. One of the plungers may be entirely withdrawn from its operative position, thus producing arbors each having only one button which may be either the end button or the intermediate button, as desired.

While I have illustrated the preferred embodiment of my invention, it is to be understood that many structural changes may be effected therein, and it is therefore to be understood that my invention is to be limited only by the scope of the appended claims.

I claim as my invention:

1. In a machine for forming arbors for incandescent electric lamps, means for successively advancing a series of arbor blanks, means for continuously rotating said blanks during a portion of their advancement, means for heating the rotating blanks locally, and means for applying successive pressures longitudinally to the said heated blanks during the heating thereof, whereby a uniform enlargement is formed on each of the said blanks.

2. In a machine for forming arbors for incandescent electric lamps, means for successively advancing a series of arbor blanks, means for continuously rotating the said blanks during a portion of their advancement, means for positively alining said blanks relative to each other, means for heating the rotating blanks locally, and means for applying successive pressures longitudinally to the said heated blanks during the heating thereof, whereby a pre-determined enlargement uniformly positioned is made on each of the said blanks.

3. In a machine for forming arbors for incandescent electric lamps, means for suc-

cessively advancing a series of arbor blanks, means for continuously rotating the said blanks during a portion of their advancement, means for positively alining the said blanks relative to each other, means for sequentially heating the blanks locally at a plurality of parts thereof, and means for applying successive pressures longitudinally to the said heated blanks during each of the sequential heatings thereof, whereby a plurality of uniformly positioned enlargements are formed on each of the said blanks.

4. In a machine for forming arbors for electric lamps, means for successively advancing a series of arbor blanks, means for heating the blanks locally, and means for applying a preliminary longitudinal pressure and a final longitudinal pressure to the said blanks.

20 5. In a machine for forming arbors for electric lamps, means for successively advancing a series of arbor blanks, means comprising a plurality of simultaneously reciprocating plungers for forming a plurality of enlargements in the said blanks, and means for applying preliminary pressure to said blanks, two sets of driving rollers for the said plungers.

6. In a machine for forming arbors for incandescent electric lamps, a rotatable carrier for successively advancing arbor blanks, endless bands engaging the carrier for rotating the blanks thereon, two sets of driving rollers for the said bands disposed on opposite sides of the said carrier, and means for positively rotating both of the said sets of driving rollers.

7. In a machine for forming arbors for incandescent electric lamps, a frame, a shaft mounted in the frame and supporting a rotatable carrier for successively advancing a series of arbor blanks, two sprocket wheels mounted on the said shaft, endless bands for imparting rotary movement to the said blanks, two sets of driving rollers for the said bands disposed on opposite sides of the said carrier, a sprocket wheel associated with each of the said sets of driving rollers, and a sprocket chain connecting each of the said roller sprocket wheels with one of the said sprocket wheels on the said shaft.

8. In a machine for forming arbors for incandescent electric lamps, a rotatable carrier for successively advancing arbor blanks, and endless bands driven by rollers and engaging the said carrier for rotating the blanks thereon, each of the said bands being arranged to have opposing surfaces adapted to frictionally engage the said blanks therebetween.

9. In a machine for forming arbors for incandescent electric lamps, a rotatable carrier for successively advancing arbor blanks, and endless bands driven by rollers and engaging the said carrier for rotating the

blanks thereon, each of said bands being arranged to have opposing surfaces adapted to travel in opposite directions.

10. In a machine for forming arbors for incandescent electric lamps, a rotatable carrier for successively advancing arbor blanks, endless bands driven by rollers and engaging the said carrier for rotating the blanks thereon, and means for applying cooling currents of air to the said carrier and the said bands, the said means comprising a casing partly inclosing one of the said band-driving rollers, a perforated pipe extending axially beneath the said carrier, and means for supplying air under pressure to the said casing and to the said perforated pipe.

11. In a machine for forming arbors for incandescent electric lamps, a rotatable carrier for successively advancing a series of arbor blanks, endless bands engaging the carrier for rotating the blanks thereon, rollers for maintaining the said bands under tension and spring-pressed rolls bearing upon the said bands for maintaining the said bands in close engagement with the said arbors.

12. In a machine for forming arbors for incandescent electric lamps, means for successively advancing a series of arbor blanks, means for forming enlargements or buttons on the said blanks, and means for varying the size and number of such enlargements or buttons, said last mentioned means including devices suitable to apply successive pressures longitudinally to the heated blanks during each of the sequential heatings thereof.

13. In a machine for forming arbors for incandescent electric lamps, means for successively advancing a series of arbor blanks past a stationary anvil member, means for rotating the said blanks around their central axes during their advance, a plunger co-operating with the said stationary anvil member for forming an enlargement in each of the said blanks.

14. In a machine for forming an enlargement upon cylindrical glass objects, a rotatable carrier for successively advancing a series of work blanks, and co-operative means for continuously rotating a plurality of the advancing work blanks during a portion of their travel, said means comprising opposing surfaces adapted to move in opposite directions and frictionally engage the blanks fed therebetween, whereby the said blanks are positively rotated when so engaged.

In testimony whereof, I have hereunto subscribe my name this 25th day of Oct., 1915.

CHARLES EISLER.

Witness:

F. T. CRAMER,

It is hereby certified that in Letters Patent No. 1,338,499, granted April 27, 1920, upon the application of Charles Eisler, of Bloomfield, New Jersey, for an improvement in "Machines for Making Filament-Supports for Incandescent Lamps," an error appears in the printed specification requiring correction as follows: Page 5, line 27, claim 5, for the words "two sets of driving rollers for" read *before they are engaged by*; and that the said Letters Patent should be read with this correction therein that the same may conform to the record of the case in the Patent Office.

Signed and sealed this 6th day of July, A. D., 1920.

[SEAL.]

M. H. COULSTON,
Acting Commissioner of Patents.
